Res. 1226

David Mc. Nair, of Roxbury, Mass.
assignor to Roxbury Carpet Company, of Boston,
Letters Patent No. 1226, dated April 3, 1860.

The schedule referred to in these ^{impressions} Letters Patent and making part of the same.

To all Persons to whom these Presents shall come:

Be it known that I, David Mc Nair, of Roxbury, in the County of Norfolk, and State of Massachusetts, have invented an ornamental design to be wrought into Carpets or other fabrics, and I do hereby declare that the same is represented in the annexed photographic drawings.

The said design I claim as my invention.
